FIG. 2

Irving K. Hessberg, INVENTOR.
BY
Hoch & Blum, ATTORNEYS

UNITED STATES PATENT OFFICE

103,616

DESIGN FOR A GLOVE

Irving K. Hessberg, New York, N. Y., assignor to Van Raalte Company, New York, N. Y., a corporation of New York

Application December 2, 1936, Serial No. 66,259

Term of patent 3½ years

To all whom it may concern:

Be it known that I, Irving K. Hessberg, a citizen of the United States, residing in New York, county and State of New York, have invented a new, original, and ornamental Design for a Glove, of which the following is a specification, reference being had to the accompanying drawing, forming a part thereof.

In the drawing:

Fig. 1 is a plan view of the back of a glove showing my new design.

Fig. 2 is a plan view of the front thereof.

I claim:

The ornamental design for a glove, as shown.

IRVING K. HESSBERG.
